COMBINED MOTOR VEHICLE AND ADJUSTABLE LOADING PLATFORM

Bernard S. Sain, 321 Charnwood Road,
New Providence, N.J. 07974

Filed Apr. 9, 1970, Ser. No. 22,346

Term of patent 3½ years

Int. Cl. D12—09

U.S. Cl. D14—3

FIG. 1

FIG. 2

FIG. 3

FIG. 4

FIG. 5

FIG. 6

FIG. 7

FIG. 1 is a perspective view of a combined motor vehicle and adjustable loading platform, showing my new design;

FIG. 2 is a reduced side elevational view thereof;

FIG. 3 is a reduced rear elevational view thereof;

FIG. 4 is a bottom plan view thereof;

FIG. 5 is a reduced rear elevational view thereof;

FIG. 6 is a view similar to FIG. 2 but showing the opposite side thereof; and

FIG. 7 is a top plan view thereof.

I claim:

The ornamental design for a combined motor vehicle and adjustable loading platform, as shown.
